UNITED STATES PATENT OFFICE.

HARRY MACCANLIS, OF NEW YORK, N. Y.

SAMPLE-CARD.

1,209,461.

Specification of Letters Patent. Patented Dec. 19, 1916.

Application filed November 11, 1915. Serial No. 60,872.

To all whom it may concern:

Be it known that I, HARRY MACCANLIS, a citizen of the United States, and a resident of the city of New York, borough of Manhattan, in the county and State of New York, have invented a new and Improved Sample-Card, of which the following is a full, clear, and exact description.

One object of the invention is to provide 10 a new and improved sample card provided with a series of sample-carrying tabs, any one of which can be readily removed and replaced by another, in case the particular pattern is sold out or discontinued, thereby 15 maintaining at all times a proper appearance of the sample card.

Another object is to hold the sample-carrying tabs securely in position on the card.

20 In order to accomplish the desired result, use is made of a sample card provided near each side edge with a pair of spaced parallel slits, and a sample-carrying tab overlying the face of the sample card and provided at 25 its ends with tongues extending through the outermost slits to the back of the card and then being bent inward to extend through the innermost slits to the front of the card underneath the tab.

30 A practical embodiment of the invention is represented in the accompanying drawings forming a part of this specification, in which similar characters of reference indicate corresponding parts in all the views.

35 Figure 1 is a plan view of an open sample book containing two sample cards; Fig. 2 is a plan view of the same; Fig. 3 is an enlarged rear face view of one of the sample-carrying tabs with portions broken out; and 40 Fig. 4 is a cross section of the same on the line 4-4 of Fig. 3.

The sample-carrying card 10 has its body made of suitable paper or like material, and the card is provided near its side edges with 45 pairs of parallel slits 11, 12 and 13, 14 adapted to be engaged by tongues 15, 16 extending from the ends of the tabs 17 carrying a sample 18 of the goods desired to be exhibited to the prospective purchasers. It 50 is understood that each tab 17 with its sample 18 thereon overlies the face of a card 10 in a sidewise direction, and the tongue 15 of each tab 17 extends first through the slit 11 to the back of the card, and it then 55 extends inwardly through the slit 12 to the face of the card underneath the tab, as

plainly indicated in Fig. 2. The tongue 16 of each tab 17 extends first through the slit 13 to the back of the card and is then bent inwardly and passed through the slit 14 to 60 extend to the face of the card underneath the tab 17 also, as plainly shown in Fig. 2. It will be noticed that by engaging the tongues 15 and 16 with the pairs of slits 11, 12 and 13, 14 as described, the tab is securely 65 held in position and the ends of the tongues 15 and 16 are completely concealed, so that the back of the card 10 presents no undesirable projections liable to be caught on the samples exhibited on the face of the next 70 following card, as will be readily understood by reference to Figs. 1 and 2. It will also be noticed that by the arrangement described any one of the sample-carrying tabs 17 can be readily removed from the card 10 75 by disengaging the tongues 15 and 16 from the corresponding slits 11, 12 and 13, 14 and lifting the tab off the card. The removed tab can be readily replaced by another one so that an unbroken series of samples are 80 displayed on the front face of the card 10.

In order to firmly stretch the sample 18 over the face of its tab 17, the sides thereof are preferably provided with flanges 19, 20, 85 bent over onto the back of the tab and to which are secured the top and bottom edges of the samples so that when the flanges 19 and 20 lie flat on the face of the card 10 the samples 18 are firmly stretched over the front faces of the tabs 17. 90

By reference to Fig. 1 it will be noticed that the tongue 15 of each tab 17 extends for a short distance on the front face of the card 10 to provide sufficient space on the tongue for receiving a numeral or other 95 character indicating the corresponding pattern of the sample 18 carried by the tab.

Two or more sample cards 10 are bound between flanges 21 and 22 formed at the back edges of a front cover 23 and a rear 100 cover 24, as plainly shown in Figs. 1 and 2. The outer faces of the flanges 21 and 22 are overlaid by strips or washers 25, 26, and fasteners 27 extend through the strips 25, 26, the flanges 21, 22 and the portions of 105 the cards 10 extending between the said flanges so as to securely fasten the sample cards in position between the covers 23 and 24. It will be noticed that by this arrangement the sample book when closed 110 presents no undesirable projections such as are usually found on sample books as now con-

structed and having the clenched ends of the fasteners as well as the heads thereof extending in the outside of the covers. Thus a large number of sample books can be 5 readily packed in a trunk or other receptacle without danger of entanglement and without injury to the hands or mutilation of the covers while handling the sample books.

Having thus described my invention, I 10 claim as new and desire to secure by Letters Patent:

A sample card provided with a sample-

carrying tab provided at its ends with tongues and at its sides with flanges bent onto the back, and a sample extending over 15 the face of the tab and secured at its edges to the said flanges.

In testimony whereof I have signed my name to this specification in the presence of two subscribing witnesses.

HARRY MacCANLIS.
